J. A. WHERRY,
RECORD SHEET OR CARD,
APPLICATION FILED JULY 29, 1921.

1,424,968.

Patented Aug. 8, 1922.

UNITED STATES PATENT OFFICE.

JOHN A. WHERRY, OF NEW ORLEANS, LOUISIANA.

RECORD SHEET OR CARD.

1,424,968.

Specification of Letters Patent.

Patented Aug. 8, 1922.

Application filed July 29, 1921. Serial No. 488,433.

To all whom it may concern:

Be it known that I, JOHN A. WHERRY, a citizen of the United States, residing at New Orleans, State of Louisiana, have invented 5 certain new and useful Improvements in Record Sheets or Cards; and I do hereby declare the following to be a full, clear, and exact description of the invention, such as will enable others skilled in the art to which 10 it appertains, to make and use the same.

This invention relates to a novel form of record sheet, and has for its object to provide a composite sheet, such as is employed in loose leaf ledgers and individual sheet or 15 card records, comprising a main section to receive the particular data to be recorded from time to time, and a separate top or caption section, with means for detachably connecting said sections, said top section 20 having heading indicia applying to the data to be inscribed on the main section, associated therewith, preferably in the form of a removable strip with the headings printed thereon, and adapted to be applied in a 25 pocket or recess formed in the connecting means between the main and top sections of the sheet, the object of the invention being to provide a permanent top or caption section, upon which the information relative 30 to the record to be kept on the main section may be applied, and which top section also carries the heading indicia, as indicated, and a main sheet section adapted to be disconnected from the top section, when the record 35 on the main sheet section has been completed, and a new main sheet section substituted therefor.

By this arrangement, there is provided a permanent caption section, having the necessary indicia applied thereto, which may be associated successively with any number of main sheet sections, thereby avoiding the necessity of applying the data and indicia to each new or substituted sheet.

The invention is illustrated in the accompanying drawings in which:

Fig. 1 is a plan view of a portion of the main sheet section and the top section, with the means for detachably connecting the 50 same.

Fig. 2 is an enlarged vertical section at the connection between the sheet sections.

Fig. 3 is a view similar to Fig. 1, showing a modified form of the invention.

Fig. 4 is a vertical section at the joint of 55 the form shown in Fig. 3.

Fig. 5 is a fragmentary perspective view of the form shown in Fig. 3.

Referring to Figs. 1 and 2 of the drawings, 1 indicates the body or main section of 60 a record sheet, such as a ledger sheet, adapted to receive data to be recorded. Heretofore, in keeping records in loose-leaf books, separate card or sheet containers and the like, whenever a sheet or card has been filled 65 with the recorded data, it has been necessary to write up the caption and heading on a new sheet or card to replace the completed one. This involves considerable labor and expense, particularly when a large number 70 of sheets or cards have to be headed up at stated intervals. The present invention provides means for avoiding these objectionable characteristics of the standard forms of record sheets or cards, by providing a 75 permanent top or caption section, such as 2, to which the main section 1 is detachably secured, so that, when the recorded data on the latter has been completed, it may be separated from the section 2 and a new section 80 1 substitute for the old.

To enable this to be applied with accuracy and expedition, the top section 2 is preferably provided along its lower edge with a creased or folded strip of fabric 3, which is 85 secured to the sheet section by suitable means, such as metallic clips or fastenings 6. Cemented to the fabric strip 3 are two transparent strips 4, 4, one on each side of the sheet, of celluloid or similar material, and 90 cemented between the lower edges of the strips 4, 4 is a folded or creased strip of fabric 5, similar to strip 3, the construction and arrangement of the strips 3, 4 and 5 being such that a transverse pocket or recess 95 8 is formed between the strips 4, 4 to receive a strip 7, upon which is printed or otherwise applied the data or headings for the various columns or sections referring to the record to be inscribed on the main section 1.

As illustrated, the strip 7 contains the heading of a ledger sheet, but, obviously, the data or heading may be changed or varied to apply to any other form or character of 105 record to be inscribed on the main section.

The folded or creased fabric strip 5 is adapted to receive the upper edge of the

main section 1, as illustrated, and said section is removably secured to the fabric strip 5 by suitable flexible clips or fastenings 6' passed through registering openings in the strip 5 and the upper edge of the section 1.

From the foregoing it will be apparent that the top section 2, when once completed and having the necessary captions and headings applied thereto, constitutes a permanent element of the device which may be employed indefinitely, and it is only necessary to remove a completed main section 1 and replace it by another section. Furthermore, inasmuch as the captions or headings 10 constitute a permanent part of the top section it is not necessary to provide the main sections with the usual column and space rulings when the sheet is intended to be employed with a typewriter for inscribing the 15 record on the main section 1.

Obviously, instead of applying the headings to a separate strip, such as 7, they may be printed or applied directly to the strips 4, 4, but in view of the fact that the application 20 of the removable strip 7 admits of the heading being changed to suit varying conditions, the advantage of the removable strip 7 is evident.

In the construction shown in Figs. 3, 4 30 and 5, the binder fabric strip 3 is preferably cemented to the lower edge of the top section 2, and the transparent connecting strips 4, 4 are made somewhat wider so as to provide ample space for a heading strip 7, and 35 also to receive a novel form of clip 10 for securing the section 1 between the strips 4, 4.

Each of the clips 10 comprises a relatively short U-bend on one end which passes through an opening in each of the strips 4, 40 so that one leg of the bend lies between the adjacent sheets 4, 4. The longer leg of the clip extends along the outer face of the strip and is provided with a rectangular bend passing through two registering openings in the strips 4, 4, the extreme end of the clip being bendable or foldable to lie 45 against the face of the opposite strip 4.

In applying the main sheet section 1 to a headed section 2 of this type, the flexible 50 ends of the clips 10 are bent at right angles to the main body portion of the clips, so that the upper strip 4 may be raised to clear the ends of the clips, then the upper edge of the section 1, which is provided with holes registering with those in the strips 4, is slipped into position between the strips 4, and the bendable ends of the clips passed through the openings in section 1 and the upper strip 4, after which the extreme ends of the clips 55 are bent down into engagement with the face of strip 4, as described.

By this particular arrangement the clips are permanently locked to one of the strips 4, and when made of metal of proper consistency, the ends of the clips may be bent 60

or deformed indefinitely without breaking the clips, so that any number of main section sheets 1 may be applied to and removed from the headed section 2.

Moreover, the particular construction of 70 the metallic clip 10 does not materially add to the thickness of the joint formed by the fabric strip 3 and the connecting strips 4, 4, so that the composite record sheet thus constructed may be readily applied to and removed from the standard forms of type-writing machines employed in transcribing data on record sheets of this general character.

Under certain circumstances, it may be 80 found expedient to dispense with the transparent strips 4, 4, and employ wider fabric strips secured to the top section 2, by clips, an adhesive, or other suitable means, so that the main section 1, may be removably 85 secured at its upper edge between said fabric strips, by clips similar to 6' or 10, in which event the heading indicia, similar to that shown on strip 7, may be printed or otherwise applied upon the outer surfaces of the 90 fabric strips.

What I claim is:

1. A record sheet, comprising a main section, a separate top section, and means for detachably connecting said sections with 95 their edges in the same plane, said top section having heading indicia applied thereto.

2. A record sheet, comprising a main section, a separate top section, facing strips applied to the lower edge of the top section, and means for detachably connecting the main section at its upper edge to said facing strips.

3. A record sheet, comprising a main section, a separate top section, facing strips 105 applied to the lower edge of the top section, and means for detachably connecting the main section at its upper edge to said strips, said top section having heading indicia applied thereto.

4. A record sheet, comprising a main section, a separate top section, transparent facing strips applied to the lower edge of the top section, means for detachably connecting the main section at its upper edge to 115 said strips, and a strip having heading indicia thereon applied between said facing strips.

5. A record sheet, comprising a main section, a separate top section, transparent facing strips applied to the lower edge of the top section, means for detachably connecting the main section at its upper edge to said strips, and a removable strip having heading indicia thereon applied between said facing 125 strips.

6. A record sheet, comprising a main section, a separate top section, transparent facing strips applied to the lower edge of the top section, means for detachably connecting 130

the main and top sections of the record sheet including a folded fabric strip engaging the lower edge of the top section, transparent strips secured to opposite sides of the 5 fabric strip and extending below the same to form a transverse pocket, and means for removably securing the main sheet section between said transparent strips.

7. A record sheet, comprising a main section, a separate top section, transparent facing strips applied to the lower edge of the top section, means for detachably connecting the main and top sections of the record sheet including a folded fabric strip engaging the 10 lower edge of the top section, transparent strips secured to opposite sides of the fabric strip and extending below the same to form a transverse pocket, and clips carried by said transparent strips to engage and 15 lock the main section in said pocket.

8. A record sheet, comprising a main section, a separate top section, transparent facing strips applied to the lower edge of the top section, means for detachably connect-

ing the main and top sections of the record 25 sheet including a folded fabric strip engaging the lower edge of the top section, transparent strips secured to opposite sides of the fabric strip and extending below the same to form a transverse pocket, a strip 30 having heading indicia thereon in said pocket, and clips carried by said transparent strips to engage and lock the main section in said pocket.

9. A record sheet, comprising separate 35 main and top sections, means for detachably connecting the adjacent edges of said sections, and a strip having heading indicia thereon carried by said connecting means.

10. A record sheet, comprising separate 40 main and top sections, facing strips applied to the lower edge of the top section, heading indicia applied to said facing strips, and means for detachably connecting the main section at its upper edge to said strips. 45

In testimony whereof I affix my signature.

JOHN A. WHERRY.
